UNITED STATES PATENT OFFICE

JULIUS A. COLLINS, OF AUGUSTA, GEORGIA

CIGARETTE AND CIGAR HOLDER

Application filed May 28, 1932. Serial No. 614,252.

This invention relates to the broad class of motoring appliances and accessories, and has more specific reference to a holder for cigars and cigarettes.

5 More specifically stated, the invention comprises a cigarette holder which includes a receptacle for the cigarette, a cigarette butt ejecting tube connected with the receptacle, and a sectional casing constituting a protective enclosure for the cigarette, said enclosure serving as an ash collector and shield to prevent the ignited particles of combustion or ashes to be blown from the lighted end of the cigarette by the wind, whereby 10 to promote safety.

Otherwise stated, the invention has to do with a cigarette holder including a unique sectional protective casing which permits the requisite circulation of air to provide for efficient combustion but at the same time constitutes a fire guard or shield which is calculated to prevent accidental burning of the smoker's apparel and then also to prevent sparks from flying from the ignited end of 20 the cigarette, whereby to permit said shield to function as a spark arrester.

The particular constructional features constituting the novelty of the invention will become more readily apparent from the following description and drawings.

In the accompanying illustrated drawings:

Figure 1 is a side elevational view of the complete holder as constructed in accordance 35 with the principles and ideas of the present invention.

Fig. 2 is a view like Fig. 1 showing the cover sections of the protective shield or casing swung to open position.

40 Fig. 3 is a top plan view of the structure shown in Fig. 1.

Fig. 4 is an enlarged detail sectional and elevational view disclosing the construction and arrangement more explicitly.

45 Fig. 5 is a view similar to Fig. 4, with the parts of the construction in normal positions.

Fig. 6 is a longitudinal sectional view taken 50 approximately on the plane of the line 6-6 of Fig. 5.

Fig. 7 is an enlarged cross section taken on the plane of the line 7-7 of Fig. 4.

Referring now to the drawings, by distinguishing reference characters, it will be observed that the mouthpiece (see Fig. 4) is 55 denoted by the numeral 8, this being of appropriate shape and heat insulation material. Attached thereto is a smoke conducting tube 9 having an enlarged head 10 fitting slidably in the cup-like receptacle 11 to contain the 60 cigarettes 12. The numeral 13 designates a suitably shaped shell which constitutes a casing for the coiled springs 14 and 15, the inner ends of these springs being located in a depression formed in the adjacent end of the 65 mouthpiece 8 as shown clearly in Fig. 4.

The mouthpiece is slidably mounted in this shell-like casing with the left hand end of the casing being formed with an annular 70 abutment flange 16 having a central opening through which the cup 11 is slidable. Incidentally, as shown in Fig. 7, the flange is provided with diametrically opposite notches 17 and the flanged inner end of the cup is provided with diametrically opposite lugs 18. 75 In assembling the cup, it is inserted through the opening in the flange 16 at which time the lugs 18 are registered with the notches 17. Then the cup is turned one-quarter of a turn to dispose the flanges 18 in the locking position shown in Fig. 7. This arrangement also 80 allows the cup to be removed at times for cleansing purposes.

It will be noted that the cup is provided with diametrically opposite hinge knuckles 85 19 and 20 with which the adjacent ends of operating links 21 and 22 respectively are connected. There are two of these links and the right hand end thereof as seen in Fig. 5 are disposed in intersecting relationship to 90 provide the requisite scissors-like action. The opposite ends of the links are attached to bearings 23 carried by clips or cleats 24 fastened to the inner intermediate portions of the complementary sections 25 and 26 of 95 the cigarette enclosing shield 27.

It will be noted also, that the free end portions of the clip 24 are provided with prongs 28 which serve as retaining fingers and embrace cigarette 12 when it is placed 100

in position as seen in Fig. 5. The inner ends of the shield sections 25 and 26 are provided with companion ears 29 pivotally attached as at 30 to diametrically opposite sides of the spring casing 13. The upper or longitudinal crown portion of the shield section 25 is formed with longitudinally spaced transverse slots 31 of appropriate ornamental configuration to define air circulation holes. 5 The section 26 is provided at its inner end with a series of small holes 32 and has its opposite longitudinal edges formed with the L-shaped air circulation notches 33. The numeral 34 merely designates a rim formed 10 around the meeting edge of the section 25, whereby to permit both sections 25 and 26 to come together in tight closing relationship 15 as shown in Fig. 1.

Attention is directed to the fact that the 20 tube 9 not only serves to conduct the smoke from the cigarette into the mouth piece 8 but constitutes a mechanical ejector for bodily ejecting the butts from the holding receptacle 11 after the cigarette has been practically consumed. The slidable mounting of 25 the mouthpiece 8 in the casing 13 permits the mouthpiece, through the agency of the spring to slide the receptacle or cup 11 through the left hand end of the casing so as to act upon 30 the intersecting links 21 and 22 to produce the desired opening and closing means for the sections 25 and 26 of the shield 27. Thus these shields are swung to open position by 35 this arrangement to permit the cigarette to be placed in position or subsequently removed.

It is evident that the initial movement of the mouthpiece 8 with respect to the casing 13 serves to open the sections 25 and 26. A still 40 further movement however, brings the ejecting head 10 into play for forcing the cigarette 12 out of the receptacle 11. To aid in holding the casing 14 it is provided on one side with a roughened finger grip or insert 35 as shown in Fig. 3.

In actual practice, the parts of the structure are of appropriate material and are of such proportions and shape as to provide the desired utility and ornamental features. 50 It is essential however, to provide a casing 13 to serve as a container and housing for the springs and to permit the slidable unit comprising the mouthpiece 8 and tube 9 to function properly therein. The casing also 55 has the additional function of a mounting for the slidable cigarette containing cup or receptacle 11.

It is also important to so construct the casing 14 as to permit it to be firmly grasped 60 between the fingers while forcing the mouthpiece 8 inwardly against the tension of the springs. The springs are of such relative tensions, as to permit the small cylinder springs 15 to come into play first to move 65 the receptacle 11 from the position seen in

Fig. 5, to the projected position seen in Fig. 4, said spring also serving to allow the tube 9 to move onward after the flanged end of the receptacle 11 comes into contact with the flange 16 with the casing in order to permit 70 the ejector 10 to come into play to force the cigarette from the receptacle.

It is evident, of course, that the movement of the receptacle 11 is sufficient to act on the links 21 and 22 to swing the casing sections 75 25 and 26 apart to permit access to be had to the interior of the shield to remove the ashes and cigarette butts, and to then permit a new cigarette to be placed in position.

It is thought that the description taken in 80 connection with the drawings will enable a clear understanding of the invention to be had. Therefore, a more lengthy description is thought unnecessary.

While the preferred embodiment of the 85 invention has been shown and described, it is to be understood that minor changes coming within the field of invention claimed may be resorted to if desired.

Having thus described my invention, what 90 I claim as new is:—

1. In a cigarette holding and ejecting device of the class described, a hollow casing open at one end and having a centrally apertured abutment flange at its opposite end, a cup-like cigarette holding receptacle slidably mounted in the aperture in said abutment flange, the inner end of said receptacle being centrally apertured, a mouthpiece slidably mounted in said casing and projecting 100 through said end of the casing, a tube connected to said mouthpiece and having its outer end slidable thru the aperture in said receptacle, said outer end of the tube being formed with an ejecting head, and a spring 105 in the casing surrounding the tube and bearing at one end against the mouthpiece and at its opposite end against the receptacle.

2. In a cigarette holding, shielding and ejecting device of the class described, a hollow casing open at one end and having a centrally apertured abutment flange at its opposite end, a cup-like cigarette holding receptacle slidably mounted in the aperture in said abutment flange, the inner end of said 115 receptacle being centrally apertured, a mouthpiece slidably mounted in said casing and projecting thru said open end of the casing, a tube connected to said mouthpiece and having its outer end slidable thru the aperture in said receptacle, said outer end of the tube being formed with an ejecting head, a spring 120 surrounding the tube and bearing at one end against the mouthpiece and at its opposite end against the receptacle, an elongated protective shield forming an enclosure and including a pair of companion sections formed with air circulating holes and provided at their inner ends with ears pivotally attached 125 to the outer end portion of said casing, a pair 130

of intersecting links arranged in said shield and pivotally connected at their opposite ends to the shield sections and receptacle respectively.

- 5 3. An accessory of the class described comprising a hollow casing open at one end and formed at its opposite end with an annular flange defining a central guide opening, said flange being diametrically notched, a cup-like cigarette receptacle slidable through the central guide opening in said flange and formed on its inner end with diametrically opposite lugs co-operable with said notches, said receptacle being formed at its outer end
10 with diametrically opposite knuckles forming hinge connections, a mouthpiece slidable in said casing and projecting through the open end thereof, a tube in said casing connected at one end to said mouthpiece, the inner end
15 of said receptacle being centrally apertured and the adjacent end of said tube adjacent to said receptacle extending through said aperture and terminating in an ejecting head located in said receptacle, a pair of coiled
20 springs confined in said casing and surrounding said tube and bearing at their inner ends against said mouthpiece and at their opposite ends against the flange and receptacle respectively, a shield in the form of an enclosure
25 for the cigarettes comprising a pair of apertured companion sections hingedly attached at their inner ends to said casing, brackets on the inner central portions of said shield sections, said brackets being formed with
30 bearings, and a pair of intersecting links pivotally connected at their outer ends to said bearings and at their inner ends to the hinge knuckles on said receptacle.
35
40 4. An accessory of the class described comprising a relatively stationary longitudinally elongated casing, a spring-return slidable unit mounted in said casing and embodying a mouthpiece projectible through one end of the casing and a companion headed ejecting tube having its headed end slidable through the opposite end of the casing, a cigarette holding receptacle slidably supported in the last-named end of said casing and having an aperture at one end admitting the headed end of said tube, a coiled spring in the casing surrounding the tube and bearing at one end against the mouthpiece and at its opposite end against said receptacle, an elongated protective shield forming an enclosure for the cigarette and including a pair of companion sections hingedly connected at their inner ends to said casing, and an operating connection between the shield sections and
45 said cigarette holding receptacle.
50
55
60 In testimony whereof I affix my signature.
JULIUS A. COLLINS.
